PRODUCTION OF THIOPHENE-FREE BENZENE

Heber Von Lauer, Gary, Ind., and George Charles Ponchaud, Joliet, Ill.

No Drawing. Application June 18, 1942,
Serial No. 447,698

9 Claims. (Cl. 260—674)

For the production of many chemical products employed in the related explosives and dye industries, there are required large quantities of pure benzene, which forms the starting material for a wide variety of such products. Thus pure benzene is employed in the manufacture of synthetic phenol, in the production of nitrobenzene which may be converted readily into aniline, and in the manufacture of toluol, to mention only a few compounds obtainable from benzene as the starting material, and whose nitration products and derivatives find wide application in the fields of explosives, dye-stuffs, and pharmaceuticals.

The most important source of benzene is bituminous coal from which it is obtained by dry distillation, it being present, therefore, in coal tar. This benzene is, in fact, the parent hydrocarbon of all of the aromatic, or carbocyclic compounds.

The production of pure benzene is rather involved. It will be recalled that not only benzene, but also numerous methyl benzenes, and many more highly condensed aromatic hydrocarbons, such as naphthalene, acenaphthene, fluorene, anthracene and phenanthrene, fluoranthrene, pyrene, chrysene, and innumerable other compounds are obtained by the dry distillation of coal. They are present in coal tar, which is produced in great quantities in the manufacture of illuminating gas and in the coke industry.

The rapid, well-known development of the chemistry of the benzene derivatives is due largely to the fact that the aromatic parent hydrocarbons are present so largely in coal tar and coke oven light oils and are accessible in large amounts through various technical industries. While in the case of the paraffins their very nature renders them unsuitable for the preparation of the aromatic bodies; the benzene hydrocarbons on the other hand, because of the readiness with which they enter into all kinds of reactions, constitute not only the systematic, but also the practical foundation for the unbuilding of the chemistry of the aromatic derivatives. Coal tar, and more especially coke oven light oils, which contains these hydrocarbons is an inexhaustible source for the preparation of benzene and numerous benzene derivatives, many of which are of highest strategic importance militarily, and also constitute the foundation of the dye industry.

while also in many instances constituting important sources of valuable pharmaceutical products.

Coal tar and coke oven light oils contain not only aromatic hydrocarbons, but also paraffins, thiophene, methylated thiophenes, phenols, pyridine bases, and other derivatives. Coke oven light oil, which is one of the greatest sources for the preparation of benzene, is usually scrubbed from coke oven gas with a straw or absorbent oil. The absorbent oil, laden with benzene homologous paraffins, thiophene, pyridine, and other compounds, is usually separated into two fractions, the lightest of which, known as primary light oil, is specifically lighter than water, and boils up to 160° C. It contains benzene, toluene, xylene associated with other materials such as resins, olefines, paraffins, thiophene and pyridine bases.

For recovering the benzene contained therein, the crude light oil is subjected to fractional distillation, removing the highly volatile forerunners, which leaves a product boiling from between about 80° C. and about 160° C. This fraction is freed from resins, olefines, pyridine bases, and other unsaturated compounds, by washing with 66° Bé, sulphuric acid in suitable amounts, for instance 540 pounds of the acid to 5,500 gallons of the oil. The acid is drained from the agitator and the acidified oil is neutralized with caustic soda, for instance a 20 per cent caustic soda solution, which both neutralizes the acid and removes the phenols from the oil.

The thus "sweetened" oil is separated from the aqueous layer and charged to a fractionating still and carefully fractionated, there being recovered "motor" benzene, "pure" benzene, toluol, and xylol of standard quality.

All grades of benzene thus normally recovered contain varying amounts of thiophene and, since the sulphur of the thiophene renders explosives produced from the benzene hypersensitive, interferes with the true shades of dyes produced from the benzene and renders toxic those pharmaceutical products originating from the benzene as well as poisons catalysts used in catalytic processes, the complete removal of the varying amounts of thiophene contained in the benzene assumes importance.

Many procedures for removing thiophene from benzene have been proposed. Among such pro-

cedures may be mentioned the reaction with aluminum chloride, or by the use of sulphuric acid of 66° Bé. gravity, or even more concentrated sulphuric acid, or by the use of "oleum" (fuming sulphuric acid). For the present purposes, all prior methods fail because the thiophene either is only partially removed or there is excessive sulphonation of the benzene, or the cost of equipment and maintenance is excessive.

The present process provides a procedure for removing thiophene from benzene either completely, or to an extent wherein any residual thiophene is so small in amounts as to be undetectable by the most sensitive reactions therefor.

In accordance with the present invention, the "motor" benzene, the "pure" benzene or the primary light oil referred to above herein is treated for the complete removal of thiophene. The "motor" grade benzene is a grade that is suitable as motor fuel and contains toluol and xylol. The "pure" benzene is what is referred to as "industrially pure," and both grades contain thiophene, the amounts of which depend upon the quality of the coal from which the benzene has been obtained. Thus, some of these benzenes and/or light oils are found to contain only from about 0.001 per cent to 0.002 per cent thiophene, while others contain upwards of 0.03 per cent of thiophene, or more. Even such small amounts of thiophene as the 0.001 per cent mentioned above are objectionable and render the benzene unacceptable for the purposes indicated above herein.

The present invention is based upon the discovery that this thiophene may be removed entirely, or at least to such low limits as to be undetectable by the most sensitive tests now known; that is, the thiophene is removed by the present process either completely, or at least to below 0.000035 per cent, which is the limit of the sensitivity of the standard isatin reaction for thiophene.

In carrying out the present invention the "motor" benzene, the "pure" benzene and the primary light oil referred to above are treated in accordance with the following specific examples which are illustrative of the process.

The process of the present invention involves, importantly, a conjoint action of sulphuric acid and starch, it being found that the presence of the starch effects the complete removal of the thiophene, which complete removal cannot be accomplished by the sulphuric acid alone, as will become apparent from the following illustrative examples of the process. While it will be seen from the examples of the process that the sulphuric acid alone effects some removal of thiophene, such removal is incomplete and does not remove the thiophene below objectionable amounts.

Any form of starch may be employed, such as corn, wheat or potato starch, but corn starch is preferred for economic reasons.

Example I

Five thousand five hundred gallons of motor benzene were charged into a suitable agitator and 140 pounds of starch were added. After the starch became thoroughly distributed through the benzene, 720 pounds of 66° Bé. sulphuric acid were added, and the entire resulting mixture was agitated at atmospheric temperatures for approximately 1½ hours. The sludge then was drained off, the batch neutralized with 20 per cent caustic soda solution and the resulting neutral oil was charged into a fractionating still. Pure thiophene-free benzene was recovered by fractional

distillation. The comparable analysis of the charge and the product was as follows:

	Charge motor benzene	Product thio- phene- free benzene
Freezing point.....	° C.....	5.19-5.30
Thiophene.....	per cent.....	0.001-0.002
Total sulphur.....	do.....	0.026

¹ Refers to a possible maximum of 0.000035 per cent which is the limit of the sensitivity of the isatin reaction.

Example II

Industrially pure benzene with a thiophene content of 0.03% was found to require larger amounts of sulphuric acid than were employed in Example I.

After preliminary tests had indicated that concentration of 8 per cent by volume of 66° Bé. sulphuric acid would be required for the removal of a thiophene content of 0.03 per cent, a sample of industrially pure benzene with a freezing point of 5.1° C. and thiophene content of 0.03 per cent, was divided into three portions and treated as follows:

1. The first portion was reserved for untreated fractional distillation only.
2. The second portion was treated with 8 per cent, by volume, of 66° Bé. sulphuric acid, agitated thoroughly for thirty minutes, neutralized with caustic soda, steam distilled, and then fractionated to recover pure benzene.
3. The third portion was mixed with starch in the ratio of 140 pounds per 5,500 gallons, treated with 8 per cent, by volume, of 66° Bé. H₂SO₄, agitated thoroughly for 30 minutes, neutralized with 20 per cent caustic soda solution, steam distilled, and fractionated to recover pure benzene. The comparative results are shown in the following table.

These portions are identified in the table as Portion 1, Portion 2 and Portion 3, respectively.

Volume of distil- late	Portion 1 freezing point	Thio- phene	Portion 2 freezing point	Thio- phene	Portion 3 freezing point	Thio- phene		
							Per cent	Per cent
50	c. c.	° C.	Per cent	° C.	Per cent	° C.		
50	5.2		0.02	5.20	0.003	5.20

60   ¹ Residue.

The foregoing examples show the highly advantageous results produced by the action of starch on the thiophene content, which is removed completely, or at least below the limit of sensitivity of isatin (0.000035%).

The isatin test for thiophene is carried out by adding 1 c. c. of the sample which may contain thiophene to 25 c. c. of a 0.05 per cent (weight per volume) solution of isatin in pure H₂SO₄, contained in a 100 c. c. cylinder. To the mixture then are added 25 c. c. of pure H₂SO₄ containing one drop of concentrated HNO₃. Upon mixing, the appearance of a blue or green color within two hours indicates the presence of thiophene. The

reaction is highly sensitive, as is indicated above, and is made quantitative through colorimetric comparison of the blue color produced by the test sample with colorimetric standards.

As the blue color is obscured by other reactions produced by unsaturates with isatin, the washing of the light oil with sulphuric acid becomes of increased importance as such washing removes all unsaturated compounds from the oil, and, therefore, none of these can contaminate the recovered benzene.

In the process only inexpensive commercial reagents are employed, reactant losses are negligible, and there is no appreciable sulphonation of the benzene.

The impurities, including the thiophene, which are removed by the starch-sulphuric acid treatment, together with the starch, collect as a sludge which is separable readily from the remainder of the treated material.

In addition to starch, other materials may be employed in a similar manner, for example sucrose and cellulose.

We claim:

1. The process of recovering thiophene-free benzene from light oil produced in coal distillation, which comprises washing the light oil with sulphuric acid to remove unsaturated compounds present in the oil, neutralizing the resulting acidified oil, separating the neutralized oil, distilling the said oil to recover therefrom various grades of benzene which contain thiophene among their impurities, treating the said benzene with starch or starch-yielding substances and sulphuric acid in amounts sufficient to remove the thiophene contained in the benzene, agitating the benzene with the starch and sulphuric acid until the thiophene contained in the benzene is reduced to from below 0.000035 per cent to complete removal, and recovering thiophene-free benzene therefrom.

2. In the process of recovering thiophene-free benzene from thiophene-containing benzene, the improvement which consists in completely removing the thiophene by agitating the thiophene-containing benzene with starch and sulphuric acid.

3. In the process of recovering thiophene-free benzene from thiophene-containing benzene, the steps which consist in agitating the thiophene-containing benzene with starch or starch-yielding substances in the presence of sulphuric acid, the starch and acid being in amounts sufficient to effect complete removal of the thiophene from the benzene, and the acid being not stronger than 66° Bé. gravity, separating the treated benzene from the sludge resulting from the agitation, neutralizing the benzene, and recovering thiophene-free benzene therefrom.

4. The process of recovering thiophene-free

benzene from thiophene-containing benzene, which comprises agitating the thiophene-containing benzene with starch or starch-yielding substances in the presence of sulphuric acid, the

5 starch and acid being proportioned in quantity to the amount of thiophene contained in the benzene being treated so as to effect complete removal of the said thiophene, continuing to agitate the benzene with the starch and acid until

10 reaction with the thiophene is complete, the acid being below a strength sufficient to produce appreciable sulphonation of the benzene, neutralizing the thus treated benzene, and recovering thiophene-free benzene therefrom.

15 5. The process of recovering thiophene-free benzene from thiophene-containing benzene, which comprises agitating the thiophene-containing benzene with starch or starch-yielding substances in the presence of 66° Bé. gravity sulphuric acid, the starch and acid being in quantities

20 sufficient to remove the thiophene completely from the benzene, continuing the agitation until complete removal of the thiophene is effected as indicated by a negative reaction with isatin, neutralizing the thus treated benzene with caustic soda, and recovering thiophene-free benzene from the thus neutralized benzene.

25 6. The process of recovering thiophene-free benzene from crude light oils produced in coal distillation which comprises agitating the crude light oil with starch or starch-yielding substances in the presence of sulphuric acid, the starch and acid being in quantities sufficient to remove the thiophene from the light oil, neutralizing the

30 thus treated light oil with caustic soda and recovering the thiophene-free benzene by fractional distillation of the thus neutralized light oil.

35 7. The process of recovering thiophene-free benzene from thiophene-containing benzene

40 which comprises agitating the thiophene-containing benzene with sulphuric acid of approximately 66° Bé. gravity and in the presence of a substance selected from the group consisting of starch, sucrose, and cellulose, the acid and sub-

45 stance being in quantities sufficient to remove the thiophene completely from the benzene, continuing the agitation until complete removal of the thiophene is effected as indicated by a negative reaction with isatin, neutralizing the thus treated benzene with caustic soda and recovering thiophene-free benzene from the thus neutralized benzene.

50 8. The process as claimed in claim 7, wherein the said substance is cellulose.

55 9. The process as claimed in claim 7, wherein the said substance is sucrose.
